UNITED STATES PATENT OFFICE.

JAMES C. WHIPPLE, OF CHICAGO, ILLINOIS.

LACE-CURTAIN STRETCHER.

SPECIFICATION forming part of Letters Patent No. 655,038, dated July 31, 1900.

Application filed November 20, 1899. Serial No. 737,808. (No model.)

To all whom it may concern:

Be it known that I, JAMES C. WHIPPLE, a citizen of the United States, residing at Chicago, in the county of Cook and State of Illinois, have invented certain new and useful Improvements in Lace-Curtain Stretchers, of which the following, when taken in connection with the drawings accompanying and forming a part hereof, is a full and complete description sufficient to enable those skilled in the art to which it pertains to understand, make, and use the same.

This invention relates to that class or kind of lace-curtain stretchers which are designed to be set up for use and folded or taken down when not in use.

One object of this invention is to obtain a lace-curtain stretcher which shall be neat in appearance, not liable to get out of order, and of moderate cost to make.

A further object of the invention is to obtain a lace-curtain stretcher of the kind named wherein no hinge or pivoted plates will be required to be used.

25 In lace-curtain stretchers of the class or kind named side rails composed, respectively, of two bars joined together at adjacent ends are secured or attached at the opposite ends to end rails, thereby obtaining a rectangular frame, such frame being ordinarily made adjustable by pivotal connections at the meeting ends of the side and end rails made through slots in one of the meeting rails. In order to construct the side rails of light ma-

35 terial and small area in cross-section, it is necessary to provide specially-constructed meeting attachments for joining the bars together which compose such side rails at the adjacent ends thereof. It is also necessary to provide

40 a cross-bar and means for attaching it near its ends to the side rails at or adjacent to the joined bars constituting such side rails; and this invention comprises a mechanism for securing together adjacent ends of the bars forming a side rail whereof the bars are not hinged together, such side rail forming one or both, as preferred, of the side rails in the curtain-stretcher embodying this invention, and mechanism for securing the end of the 45 cross-bar to such connecting mechanism and to the adjacent ends of the bars forming such side rail or rails.

In the drawings referred to as forming a part of this specification, Figure 1 is a plan view, on a smaller scale than are the remaining figures of the drawings, (none of the drawings being, however, to scale,) of a lace-curtain stretcher embodying this invention; Fig. 2, a bottom plan view of the adjacent ends of the bars forming one of the side rails of the curtain-stretcher; Fig. 3, a vertical sectional view of one of the side rails on line 3 3 of Fig. 1, viewed in the direction indicated by the arrows; Fig. 4, an elevation on line 4 4 of Fig. 1, viewed in the direction indicated by the arrows; Fig. 5, a bottom plan view of a modification of the connecting mechanism illustrated in bottom plan view in Fig. 2; Fig. 6, an elevation of a modification of the connecting mechanism illustrated in Figs. 1 to 5, both inclusive; and Fig. 7 is a bottom plan view of the mechanism illustrated in Fig. 6.

A reference-letter applied to designate a given part in one figure of the drawings is used to indicate such part throughout the several figures wherever the same appears.

A and B are the side rails of the curtain-stretcher embodying my invention, and C and D the end rails thereof. Side rail A comprises bar a, bar a', and connection E. Side rail B comprises bars b b' and connection F. (See Fig. 2.)

G is the connecting-bar, extending from side rail A to side rail B.

H H are bolts attaching the ends of the side and end rails together.

g' g' are washers on bolts G' G' H H, respectively, and g² g² are butterfly-nuts on such bolts G' G' H H, respectively.

G' G' are bolts extending through holes in connecting-plate E and connection F, as hereinafter more fully shown and described.

Connecting mechanism E comprises the plate e, turned up on its side edges, as at e' e', and the bolts G' G', extending through holes in the plate e, with washers g' g' and nuts g² g², and the bolt G², extending through the connecting-bar G, plate e of the connection, washer g' on the last-named bolt, and a butterfly-nut. In this connection the ends of the bars a a' are grooved vertically to permit the bolt G' last above described to pass between such ends.

Connection F comprises plate f, bolts G' G'

and G^2 , and washers $g' g'$, with the butterfly-nuts $g^2 g^2$ on such bolts, respectively. The plate f is provided with the holes $f' f^2$ for bolts $G' G^2$ and slot f^3 for a bolt to pass through, respectively.

The connecting-bar G is attached firmly in place to side rail A by bringing such connecting-bar up against the under side of plate e of connection E , as is well shown in Fig. 3 of the drawings, passing the bolt G' upward through the connecting-bar and plate e and through between the ends of the bars $a a'$ in the slot or vertical groove $a^2 a^2$ on the ends of such bars, and then placing the washer g' on such bolt, with the butterfly-nut g^2 firmly set in place. The lines indicating such grooves $a^2 a^2$ are coincident in Fig. 3 with the lines indicating the bolt G^2 and in Figs. 2 and 5 with the circles indicating the holes $f^2 f^2$ in plates f and f^4 , respectively, and in Fig. 7 with the circle indicating similar vertical grooves in parts $e^2 e^3$ of plate E .

The connecting-bar G is secured in place to side rail B in substantially the same way—that is, by bringing such connecting-bar up against the under side of the plate f of connection F , as is well shown in Fig. 4 of the drawings, passing the bolt G' upward through the connecting-bar and plate f and through the bars $b b'$, (between the ends of such bars,) and then placing the washer g' on such bolt, with the butterfly-nut g^2 firmly set in place.

The connection F is attached in place and to the bars $b b'$ by the bolts $G' G'$, (see Fig. 4,) passing through holes provided therefor in the respective bars $b b'$ and through the plate f , (one of such bolts passing through hole f' and the other through slot f^3 , as shown in Fig. 2,) and then setting the butterfly-nuts firmly in place on such bolts. The cross-bar G is attached to this connection by passing the bolt G^2 through the connecting-bar, the plate f in the vertical grooves at the ends of the bars $b b'$, and washer g' , and then securing the butterfly-nut on the bolt by turning it up against the washer. (See Fig. 4.)

In the modification of connection E , which is illustrated in Figs. 6 and 7 and lettered E' , the plate is cut on lines e^5, e^6, e^7, e^8 , and e^9 to obtain parts e^2 and e^3 . Parts $e^2 e^3$ are secured to the respective bars $a a'$ by screws $e^4 e^4$. The parts $e^2 e^3$ are placed between the connecting-bar G and the bars $a a'$, forming rail A , as is illustrated in Fig. 6 of the drawings. Such connecting-bar G is removed in Fig. 7 to give a view of the several lines e^5, e^6, e^7, e^8 , and e^9 . In this modification the bolt G^2 is used, as in the constructions illustrated in the remaining figures of the drawings, to attach the connecting-bar G in place to the rails, with parts $e^2 e^3$ interposed between the connecting-bar and the rail.

In the modification of connection F , which is lettered F' in Fig. 5 of the drawings, the plate is lettered f^4 and is provided with hole f^2 for bolt G^2 to pass through, as in plate f of connection F , and with the slots $f^6 f^5$ for the

bolts $G' G'$ to pass through. This plate f^4 is secured to the bars $b b'$ of side rail B by the bolts $G' G'$, passing through the slots $f^5 f^5$, respectively, and through the bars $b b'$, such bolts having thereon washers $g' g'$ and butterfly-nuts $g^2 g^2$ in the same relative position and in the same manner as is shown in Fig. 4 relative to connection F . In the use of this modification F' , as well as in the use of the construction illustrated in Figs. 2 and 4, (connection F ,) bars $b b'$ can be folded parallel to each other upon taking out the bolts $H H$ at the ends thereof, respectively, without taking bolts $G' G'$ out of such bars $b b'$, it being simply necessary to loosen the butterfly-nuts $g^2 g^2$ on such bolts.

The connecting-bar G may be disconnected from the connections $E E' F F'$, respectively, by taking out the bolt G' , or it can when the device is in use be disconnected from the connection on one side of the curtain-stretcher embodying the invention and allowed to remain connected up, but loosened, as stated, on the other side of such curtain-stretcher when the connection F or F' is employed.

In the modification lettered E' and illustrated in Figs. 6 and 7 the screws $e^4 e^4$, securing the plate E' (parts $e^2 e^3$, respectively) to the bars $a a'$, are used as substitutes for the bolts $G' G'$, with washers $g' g'$ and nuts $g^2 g^2$ thereon, illustrated in the remaining connections of the drawings, and hence such bolts, washers, and nuts are omitted from this construction.

Having thus described my invention, what I claim as new, and desire to secure by Letters Patent, is—

1. In a lace-curtain stretcher, side rails joined to end rails, a center-bar connecting the side rails of the stretcher, such side rails comprising, on one side of the frame, bars secured together by a connecting-plate provided with a central opening and diagonally-extending openings near the ends thereof, bolts passing through such end openings and through the bars, respectively, nuts on the bolts and washers, and a bolt passing through the central opening in the plate, through the cross-bar which is secured to the connection on the other side rail and between the ends of the side bars, and on the other side of the frame-bars joined together by a connecting-plate provided with openings therethrough, bolts passing through such openings and through the bars, an additional bolt passing through such plate, the bar connecting the side rail with the side rail on the opposite side of the frame, and between the ends of the side bars, and washers and nuts on the several bolts; substantially as described.

2. In a curtain-stretcher, a side rail comprising bars joined together at adjacent ends and a cross-bar attached to the under side of the side rail and extending across the frame to the other side rail thereof, such bars joined by a connection consisting of a plate having a central opening and additional openings therethrough adjacent to the ends thereof,

the central opening being substantially circular and at least one of the remaining openings being slot-shaped and extending radially to the turning-point of the rail ends, bolts 5 extending through the several openings in the plate and through the side bars, the bolt in the central opening also extending through the cross-bar, with washers and nuts on the

several bolts, with the plate interposed between the side rail and the cross-bar; substantially as described.

JAMES C. WHIPPLE.

In presence of—

CHARLES TURNER BROWN,
O. C. PETERSON.
